UNITED STATES PATENT OFFICE.

NORMAN W. CUMMINS, OF BRIDGEPORT, CONNECTICUT, ASSIGNOR TO THE BURNS & BASSICK COMPANY, OF BRIDGEPORT, CONNECTICUT, A CORPORATION OF CONNECTICUT.

GREASE-CUP.

1,088,770.

Specification of Letters Patent.

Patented Mar. 3, 1914.

Application filed March 26, 1913. Serial No. 756,989.

To all whom it may concern:

Be it known that I, NORMAN W. CUMMINS, a citizen of the United States, residing in the city of Bridgeport, county of Fairfield, State of Connecticut, have invented certain new and useful Improvements in Grease-Cups; and I do declare the following to be a full, clear, and exact description of the invention, such as will enable others skilled in the art to which it appertains to make and use the same.

This invention relates to certain new and useful improvements in grease cups and pertains more particularly to the means in a force feed cup for preventing retrograde movement of the cap that constitutes the feeding element.

The primary object of the present invention is to provide simple, inexpensive, novel and improved means for the purpose of preventing retrograde movement of the grease cup, and to this end the invention consists essentially in the provision of a non-rotating leather or similar disk which is exteriorly threaded and which, by frictional contact with the cap, prevents rotation thereof, except when considerable force is applied to the cap in order to rotate same to effect feed of the grease.

In the drawings: Figure 1 is a side elevation, partly broken away, and in section of the invention; Fig. 2 is a section on the line 2—2 of Fig. 1; Fig. 3 is a section on the line 3—3 of Fig. 1; and Fig. 4 is a detached perspective view of the leather disk.

The body 1 of the grease cup has an interiorly threaded, reduced lower end 2, the upper end of the body being formed with an annular flange 3. A reinforcing member 4 has an interiorly extending flange 5 which is formed with an opening that conformably receives the body 1, which latter is of hexagonal shape in cross section. The upper free end portion of the reinforcing member 4, that is of cup shape, is forced or spun inwardly so as to engage on the top face of the flange 3 of body 1, as indicated at 6, whereby the flange 5 and the inwardly forced portion or flange 6, clamps the flange 3 between said flanges 5 and 6, as depicted in Fig. 1. The peripheral portion of the reinforcing member 4 is externally threaded, and engages with the interior threads of a cap 7. A leather or similar disk 8 is formed

with a hexagonal opening 9 that conformably receives the body 1 in order to prevent relative rotation between the body and the disk, the disk being exteriorly threaded so as to engage with the interior threads of cap 7, and having its upper face impinged against the flange 5 of the reinforcing member 4. The disk 8 is held in engagement with the flange 5 by means of teats 10 which latter are formed by shaving or cutting the angular portions of the hexagonal body, and forcing said portions firmly against the under face of the disk 8, whereby the latter is held in position at a plurality of points without the use of any additional element, since the fastening means constitutes an integral part of the body 1.

As above stated, the leather disk exerts sufficient friction upon the threads of the cap 7 so as to hold the latter against backward movement without the exertion of considerable manual force. A further and important decided advantage, which the invention presents, is that the teats 10 may, by means of a punch, be forced toward the flange 3 to any extent desired so as to increase the degree of compression of the disk 8, with the result that the frictional or binding engagement that said disk exerts on the threads of cap 7 is increased, in order to exert any desired pressure upon said threads. Should the friction that the disk exerts upon the threads of the cap 7 be lessened, for any reason, it will be obvious that by forcing the teats toward the flange 5, the disk 8 can be compressed to any desired extent so as to exert necessary frictional contact with the threads of cap 7, to attain the purpose of the invention.

What is claimed is:

1. In a grease cup, an angular body formed of malleable material, an exteriorly threaded reinforcing member secured to the body and having an inwardly extending base flange, an interiorly threaded cap engaged over and with said threads of the reinforcing member, a leather or similar disk externally threaded and provided with an opening that receives the body, said disk having its upper face engaged with the flange of the reinforcing member and having its threads frictionally engaged with the threads of the cap, the angular portions of the body having displaced material engaged

with the under face of the leather disk to hold same at a plurality of spaced points and against the flange of the reinforcing member.

- 5 2. In a grease cup, a body formed of malleable material having an angular cross-section and an abutment adjacent its upper end, a leather or similar disk having an opening which receives the body and is held 10 from rotation by the latter, an interiorly threaded cap on the body, said disk having its periphery threaded and frictionally engaged with the threads of the cap, and a series of spaced independent means integral 15 with the body and engaged with the under face of the disk to hold same against the abutment, said means being capable of being forcibly moved against the disk to govern the extent of compression of the latter.
- 20 3. In a grease cup, a body formed of malleable material having an angular cross-section and an abutment adjacent its upper end, a leather or similar disk having an opening which receives the body and is held 25 from rotation by the latter, an interiorly

threaded cap on the body, said disk having its periphery threaded and frictionally engaged with the threads of the cap, and teats integral with the body and engaged with the under face of the disk to engage same at a plurality of points to hold same in position, said teats being capable of being forcibly moved against the disk to adjustably compress the latter.

4. In a grease cup, a body formed of 35 malleable material, a cap threaded over the body, an abutment on the body, a disk on the body engaged with said abutment and having a threaded periphery to frictionally engage the threads of the cap, and teats 40 integral with the body and being capable of being forcibly moved to engage the disk to hold same against said abutment.

In testimony whereof I affix my signature in presence of two witnesses.

NORMAN W. CUMMINS.
